(57) **CLAIM**

The ornamental design for an apertured air conditioner panel with movable door, as shown and described.

DESCRIPTION

FIG. 1 is a perspective view of the top, rear and one side of an apertured air conditioner panel with movable door showing our new design;

FIG. 2 is a side elevational view of said one side, the opposite side being a mirror image thereof;

FIG. 3 is a rear elevational view thereof;

FIG. 4 is a top plan view thereof;

FIG. 5 is a bottom plan view thereof;

FIG. 6 is a front elevational view thereof; and,

FIG. 7 is a view similar to FIG. 1 with the door in an intermediate position.
